DESIGN FOR A LIGHTING FIXTURE FOR TYPEWRITERS

Edward L. Brown, New York, N. Y.

Application March 24, 1936, Serial No. 61,761

Term of patent 3½ years

To all whom it may concern:

Be it known that I, Edward L. Brown, a citizen of the United States and a resident of New York, in the county and State of New York, have invented a new, original, and ornamental Design for a Lighting Fixture for Typewriters, of which the following is a specification, reference being had to accompanying drawing, forming a part thereof in which:

Fig. 1 is a front elevational view of a lighting fixture for typewriters, showing my new design; and

Fig. 2 is a side elevational view thereof.

I claim:

The ornamental design for a lighting fixture for typewriters, as shown.

EDWARD L. BROWN.
